Filed May 6, 1966, Ser. No. 2,189

Term of patent 14 years

(Cl. D71—1)

FIG. 1.

FIG. 2.

FIG. 3.

FIGURE 1 is a perspective view of a combination swimming aid and flag support embodying my design, as seen from a high angle;

The fin simulating member, as indicated in FIGURES 1 and 2, is characterized on each side, by a red color intersected diagonally by a white stripe.

The dominant features of my design reside in the portions shown in full lines in the drawings.

I claim:

The ornamental design for a combination swimming aid and flag support, substantially as shown and described.
